UNITED STATES PATENT OFFICE.

HERMAN JAKOBSSON, OF PHILADELPHIA, PENNSYLVANIA.

CARTRIDGE-CASE EXTRACTOR FOR GUNS.

1,290,835.

Specification of Letters Patent.

Patented Jan. 7, 1919.

Application filed February 28, 1917. Serial No. 151,407.

To all whom it may concern:

Be it known that I, HERMAN JAKOBSSON, a citizen of the United States, residing at Philadelphia, county of Philadelphia, and 5 State of Pennsylvania, have invented a new and useful Improvement in Cartridge-Case Extractors for Guns, of which the following is a full, clear, and exact description, reference being had to the accompanying drawings, which form a part of this specification.

10 The object of my invention is to provide a new and improved cartridge case extractor. The invention is particularly applicable to that well known type of gun in 15 which the breech block moves in and out of the breech in a vertical, horizontal or inclined plane, the opening movement taking place, preferably, automatically during the counter recoil of the gun and the closing 20 movement also taking place automatically on the insertion of a fresh projectile and cartridge case. The invention is also applicable to a gun in which the breech block is manually operated.

25 A preferred embodiment of the invention is shown in the accompanying drawings, in which,—

Figure 1 is a horizontal sectional view of the breech end of the gun with the breech 30 block in its open position.

Fig. 2 is a transverse section through the breech end of the gun on the line 2—2 of Fig. 3.

Fig. 3 is a vertical section on the line 3—3 35 of Fig. 2.

Fig. 4 is a view, similar to Fig. 3, showing the parts in a different position.

Fig. 5 is a plan view of the cartridge case extractor.

40 Fig. 6 is a perspective view of the breech block.

Fig. 7 is an inverted plan view of the breech block, together with the cartridge case extractor.

45 Fig. 8 is an enlarged perspective view of the cartridge case extractor.

Fig. 9 is an enlarged perspective view of the cam plate for operating the cartridge case extractor.

50 30 is the gun with its chamber 31 and breech end 32. The latter is provided with a rearward opening 33 and a transverse opening or housing 34 in which the block or wedge 35 is arranged to slide in and out in 55 the breech. The rear wall 36 of the housing is slightly inclined in conformity with the

taper of the block 35, so that when the mechanism is open, that is, when the block moves out transversely to the bore axis, it may have a slight rearward movement. To 60 insure the breech block maintaining contact with the wall 36 in whatever position the breech block may be, a gib 37 and a corresponding groove 38 are provided respectively in the housing and the block, the direction of the gib and groove being parallel 65 with the wall 36.

An operating crank 39, journaled in a lug on the breech 32 and engaging, by means of its head 40, a cam groove 41 in the block 35, 70 controls the movement of the block. The crank 39 is actuated by a lever 42, having a handle 43 for manual operation, and connections (not shown) at 44 with some non-recoiling part of the gun carriage, for automatic 75 operation in a suitable manner.

In the center of the block is a bore or chamber for the firing gear, which comprises a firing bolt or hammer 45, a firing pin 46, a cocking sleeve 47, a trigger 64 for cocking 80 and firing the gun, and other associated mechanism which need not be further described, the same not being embodied in the invention forming the subject-matter of this application, but being fully described, 85 shown and claimed in an application of even date herewith, Serial No. 151,406.

The extractor 80 for the cartridge case 51 has a short arm 81 with a lip 81^a fitting under the rim of the cartridge case 51. The 90 long arm extends rearwardly and lies in a suitable guiding groove in the gun breech in such a manner that when the cartridge case is pushed fully in, the rear end of the long arm does not bottom in the groove, as 95 shown in Fig. 3. At the junction of the two arms is formed a rounded heel 82 which rests in a socket provided in the breech. This heel constitutes a rigid connection between the two arms. The extreme end of the 100 long extractor arm has a lug 83 provided with a transverse slope 84 and a forward slope 85. When the breech block is moving out, the transverse slope 84 is first struck by a corresponding cam surface 86 on the block. 105 As a consequence, the extractor will turn on its heel 82 which is unyielding and act as a crow-bar, thus loosening the cartridge case in the chamber. As the block proceeds to run out, the forward extractor slope 85 is 110 acted upon by a similar cam surface 87 on the block, thereby causing the extractor to

move rapidly to the rear, thus imparting a quick ejection of the cartridge case. To prevent rattling of the extractor when free and to insure full control between the inclined cam surfaces, a plunger 88, actuated by a spring 89, tends to push the extractor inward. The plunger also acts as a latch to hold the extractor in its rearward position, as shown in Fig. 4, and a small notch or recess 90 on the extractor is for this purpose provided for the point of the plunger. The spring 89 actuates a second plunger 91, which constitutes a latch for the collar of a stop bolt 92. The end of bolt 92 works in a groove 93 in the breech block (said groove being inclined parallel with the wall 36), thereby limiting the travel of the block in the breech. The block and the extractor are provided with abutment surfaces 94 and 95 respectively which, upon contact, act to hold the block open.

The operation of the mechanism is as follows:

On opening the mechanism, which will be accomplished either by hand, or, if an automatic opening device is employed by the latter turning the operating crank 39 during the recoil or counter recoil of the gun, the slope 86 on the underside of the breech block 35 operates on the slope 84 of the extractor, tilting it in transverse direction, thereby loosening the cartridge case. A moment later the slope 87 on the breech block will hit the forward slope 85 on the extractor, which is, as a consequence, violently thrown back into the position shown in Fig. 4, bringing with it the empty cartridge case, which is thus ejected from the breech. This action is still more emphasized by the slightly rearward travel of the block, synchronously with its transverse withdrawal, caused by the inclined direction of the guide groove 93 engaging with the bolt 92. The block is given a little longer travel than would be necessary for the ejection of the empty cartridge case, this being done to insure the engagement of the plunger 88 in the extractor recess 90 which will prevent the rebounding of the extractor. In this manner the abutment 94 on the block is sure to be beyond the corresponding flat surface 95 on the extractor lug. When the block is directly after pushed inward by the operating spring, acting on the hand lever at 44, in case the gun is automatically closed, the extractor lug now stops further closing movement of the block.

Upon again loading the gun, the rim of the cartridge case 51 engages the toe 81^a on the arm 81 of the extractor, drawing the latter forward, thus releasing the block, which will now be pushed in to close the mechanism actuated by the operating crank 39.

The portion of the breech block carrying

a separate piece 99, as shown in Fig. 9, which may be inserted into the breech block and secured to its under surface, thus enabling it to be easily renewed when worn.

Having now fully described my invention, 70 what I desire to claim and protect by Letters Patent is:

1. In a cartridge case extracting mechanism for guns, the combination with a gun having a breech and a sliding block therein, 75 of an extractor having two arms and a heel at the junction of the arms, the breech having a longitudinal groove for the extractor and a socket for the heel, one of the extractor arms engaging the cartridge case, and cams 80 on the block adapted, as the block is withdrawn, to first tilt the extractor on its heel and then quickly move it in its groove.

2. An L-shaped cartridge case extractor for guns having a movable breech block, 85 the two arms being of unequal length, a toe on the end of the short arm to grip under the cartridge case rim, a rounded heel forming the connection between the two arms of the extractor, the long arm tapering in the 90 direction of its rear end, a lug at the end of the long arm, said lug being provided with inclined surfaces sloping transversely and longitudinally to said long arm respectively; the breech block being provided with correspondingly inclined surfaces, whereby the block when opened will contact first with the transversely inclined surface to tilt the extractor around said heel and thereupon contact with the longitudinally sloping surface to give the extractor a sudden straight 100 rearward movement in the longitudinal direction of its long arm.

3. A combined cartridge case extractor and ejector for guns having a slidable breech 105 block; said extractor being constructed on the principle of a crowbar having a long and a short arm rigidly connected; the short arm having a thin edge intended to engage the cartridge case rim; a rounded heel 110 formed at the corner of connection of said arms; a transversely sloping surface and a longitudinally sloping surface on said long arm, the breech block being provided with correspondingly sloping surfaces and the 115 gun with a socket for said heel and a housing for said long arm running in a direction parallel to the gun axis; whereby, upon the block being moved to open, said transversely sloping surfaces are first made to contact, 120 thus swinging the extractor on its heel, and said longitudinally sloping surfaces thereupon made to contact, thus sliding the extractor rearwardly in said housing, thereby causing the cartridge case first to be extracted and then ejected from the gun chamber.

4. A combined cartridge case extractor and ejector for guns having a slidable breech block; said extractor being constructed on the principle of a crowbar having a long 130

and a short arm rigidly connected; the short arm having a thin edge intended to engage the cartridge case rim; a rounded heel formed at the corner of connection of said arms, a transversely sloping surface and a longitudinally sloping surface on said long arm, the breech block being provided with correspondingly sloping surfaces and the gun with a socket for said heel and a housing 5 for said long arm running in a direction parallel to the gun axis; a spring actuated plunger in the gun, the extractor having a recess for engaging with said plunger where the extractor stands in its retracted position;

whereby, upon the block being moved to 15 open, said transversely sloping surfaces are first made to contact, thus swinging the extractor on its heel, and said longitudinally sloping surfaces thereupon made to contact, thus sliding the extractor rearwardly in 20 said housing, thereby causing the cartridge case first to be extracted and then ejected from the gun chamber, and the extractor to be locked in its rearward position.

In testimony of which invention, I have 25 hereunto set my hand, at Philadelphia, on this 12th day of February, 1917.

HERMAN JAKOBSSON.
